Inventor

Charles J. Howe,

Charles J. Howe

Attorneys

UNITED STATES PATENT OFFICE.

CHARLES J. HOWE, OF DETROIT, MICHIGAN.

PIVOT.

Application filed March 9, 1921. Serial No. 450,830.

To all whom it may concern:

Be it known that I, CHARLES J. HOWE, a citizen of the United States of America, residing at Detroit, in the county of Wayne 5 and State of Michigan, have invented certain new and useful Improvements in Pivots, of which the following is a specification, reference being had therein to the accompanying drawings.

10 This invention relates to a pivot, of a form especially suited for use with windshields of automobiles or with such a visor as forms the subject matter of my co-pending application, Serial No. 450,829, filed March 9, 15 1921.

The primary object of my invention is to provide a pivot of this general character which will be simple in construction and readily formed from sheet metal by stamping operations.

A further object is to provide means for adjusting the tension of the spring pawl member to suit varying conditions.

With the above and other objects which will appear in the specification, my invention consists in the parts and combinations thereof or their equivalents as hereinafter described and set forth in the claims.

In the drawing, 30 Figure 1 is a front elevation of the spring pawl in place in the cup casing, which is usually attached to the movable member;

Fig. 2 is an elevation of the interior of the opposed ratchet member with which the 35 spring pawl co-operates;

Fig. 3 is a rear elevation of the pivot member shown in Fig. 1;

Fig. 4 is an elevation of the exterior of the pivot member shown in Fig. 2;

40 Fig. 5 is a vertical section on the line V—V of Fig. 4; and,

Fig. 6 is a perspective view of a modification.

The pivot consists of two relatively movable members, one of which, for purposes of description, will be termed the fixed member, and the other, the movable member. The movable member consists of a cup shaped element 10, preferably of sheet metal, having a 45 punched up at its center a boss 11 having a central aperture to receive the pivot 12. At equal distances from this central aperture are three struck up lugs 13 arranged with confronting faces at substantially sixty degrees to each other, the three lugs acting as 50 confining walls for a triangular spring pawl

member 14. Secured to the outside of the cup shaped member 10 is a bracket element 15 which may consist of a casting secured to the cup member 10 by rivets 16. 60 The member 15 is provided with lugs 17 adapted for attachment to the windshield or other member to be pivotally mounted.

The fixed member consists of a circular ratchet member 18 provided with a series of 65 depressions 19 at equal distances from the center of the plate. An angular bracket member 20 which may be cast or stamped from sheet metal is suitably secured to the ratchet member or plate 18 as by rivets 21. 70

The pivot 12 extends centrally through the boss 11, the center of the plate 18 and the bracket 20 and at its outer end receives a nut 22 which may be locked in adjusted position by the cotter pin 23. The pawl member 14 75 is provided at each of its corners with bosses 24 which may be formed by stamping up the metal and each of these bosses 24 engages a depression 19. The member 14 being formed of a sheet of spring metal sup-

ported at its center by the boss 11 is free 80 at its corners to yield sufficiently to allow the bosses 24 to ride out of the depressions 19 as the movable pivot member is rotated upon the pivot 12. The tension of the ratchet 85 member 14 may be adjusted by tightening or loosening the nut 22 upon the pivot bolt 12 so that greater or less force will be required to spring the bosses 24 out of the depressions 19. The bosses 24 being spaced around the 90

circle of depressions 19 at three points equally distant from each other, the tension due to the spring 14 is equally distributed on all sides of the pivot members 12.

In the modified form shown in Fig. 6, lugs 95 25 bent up at one edge of the ends of two metal terminal strips 26 are secured by rivets 27 to the plate 10, the flanges 25 and strips 26 taking the place of the member 15 with its flanges 17.

From the above description it will be apparent that there is provided a device of the character described, possessing the particular features of advantage before enumerated as desirable, but which obviously is susceptible of modification in its form, proportion, details of construction and arrangement of parts, without departure from the principle involved or sacrificing any of its advantages.

While in order to comply with the statute, 110 the invention has been described in language more or less specific as to structural features,

it is to be understood that the invention is not limited to the specific details shown, but that the means and construction herein disclosed comprise but two of many modes of putting the invention into effect, and the invention is therefore claimed in any of the forms or modifications within the legitimate and valid scope of the appended claims.

I claim:

- 10 1. A pivot construction comprising a ratchet member having a series of depressions therein at equal radial distances from the center and a co-operating triangular spring pawl having elevated portions near each corner adapted to engage depressions in the ratchet member at points substantially equi-distant from each other, and means for adjusting the tension of the spring pawl.
- 20 2. A pivot construction comprising a fixed member consisting of a bracket and a ratchet member rigidly secured thereto and having a series of depressions equally spaced from a center and a relatively movable member comprising a bracket portion, a cup shaped casing secured thereto and having a plurality of lugs arranged upon its inner face, a spring pawl consisting of a triangular resilient plate having bosses near its corners adapted to engage depressions in the ratchet
- 25 30 plate, the lugs in the cup shaped member engaging the triangular pawl member to

prevent rotary movement and means for rotatably connecting the fixed and movable members and for adjusting the tension of the spring pawl.

3. A pivot construction comprising a ratchet member having a series of depressions arranged at equal radial distances from a center and a relatively movable member rotatable upon a pivot concentric with the depressions of the ratchet member, said relatively movable member comprising a cup shaped casing having a plurality of lugs within the cup and a central boss, and a spring pawl member substantially triangular in shape having bosses near each corner engaging depressions in the ratchet member, the central portion of the spring pawl member lying in contact with the central boss of the cup shaped casing, and means upon the pivot engaging the central boss of the movable member and the central portion of the ratchet member, whereby the distance from one to the other may be varied to adjust the tension of the spring pawl.

In testimony whereof I affix my signature in presence of two witnesses.
